UNITED STATES PATENT OFFICE.

ORIN C. FENLASON, OF HOQUIAM, WASHINGTON.

BEER-CARTON.

1,125,828.

Specification of Letters Patent.

Patented Jan. 19, 1915.

Application filed December 8, 1913. Serial No. 805,403.

To all whom it may concern:

Be it known that I, ORIN C. FENLASON, a citizen of the United States, residing at Hoquiam, in the county of Chehalis and State of Washington, have invented a new and useful Beer-Carton, of which the following is a specification.

The invention relates to improvements in beer cartons. The object of the present invention is to improve the construction of boxes and packages for shipping beer and other commodities, and to provide a simple, strong and efficient beer carton of inexpensive construction, adapted to be readily manufactured from non-homogeneous material, such as wood veneer, and capable of holding a plurality of bottles of beer and of being shipped in cases and handled separately.

A further object of the invention is to provide a veneer box or package of this character, designed particularly for shipping beer in light bottles, and capable of effectually excluding the light to prevent the same from causing a deterioration of the beer.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction, within the scope of the claims, may be resorted to without departing from the spirit or sacrificing any of the advantages of the invention.

In the drawings:—Figure 1 is a perspective view of a beer carton, constructed in accordance with this invention, portions of the outer layer or thickness of the cover being broken away to illustrate the construction more clearly. Fig. 2 is a transverse sectional view of the beer carton. Fig. 3 is a longitudinal sectional view of the same. Fig. 4 is a perspective view of the body of the carton. Fig. 5 is a similar view of the cover. Fig. 6 is a plan view of one end of the body of the carton, showing a loose arrangement of the partitions.

Like numerals of reference designate corresponding parts in all the figures of the drawings.

In the accompanying drawings in which is illustrated the preferred embodiment of

the invention, the body 1 of the box or carton, which is rectangular, is formed of inner and outer sheets 2 and 3 of veneer arranged in pairs, which are disposed at right angles to each other, the members of each pair being overlapped at their inner side or longitudinal edges to stiffen the box at the center and prevent deflection, and at the same time exclude the light.

By constructing the body of the box of four separate sheets or pieces of veneer and arranging them in this manner, a structure of great strength and durability is provided and at the same time knotty pieces of wood may be employed in the manufacture of boxes, as the knots or holes of one sheet will probably be covered by another sheet.

The strips or sheets of the inner and outer layers 2 and 3 are scored equi-distant of their ends, and the terminal portions are bent upwardly to form flanges or sections 4 and 5 of the side and end walls of the body 1 of the box or package and are secured within a band 6 by staples 7 or other suitable fastening means. The band 6, which with the flanges or sections 4 and 5 form rigid side and end walls, consists preferably of a single strip of veneer scored at the corners of the box, and having its terminal portions 8 and 9 overlapped, as clearly illustrated in Fig. 4 of the drawings. The terminal portion 8 is preferably of a length equal to the width of the box, and the other terminal portion 9, which is narrow, is fitted against the outer face of the relatively long terminal portion 7. While the overlapped terminals of the strips are shown at one end of the box, they may be at either side thereof.

The cover 10 of the box is constructed substantially the same as the body, being composed of inner and outer layers or veneer sheets 11 and 12 arranged in pairs, the members of each pair being overlapped and the pairs being disposed at right angles to each other. The sheets or pieces of the inner and outer layers 11 and 12 are scored equi-distant of their ends, and the terminal portions are bent downwardly to form flanges or sections 13 and 14, which are secured within a band 15 by staples 16. The band 15, which preferably consists of a single strip of veneer, is scored at the corners of the box and is of a length to provide overlapping terminals 17 and 18, the overlap being shown at one side

of the cover, but it may be at one end similar to the overlap of the body strip 6.

The interior of the body of the box is divided into central and side bottle receiving compartments 19 and 20 by spaced partitions 21, consisting of separate strips of veneer of uniform length scored equi-distant of their ends and bent horizontally to provide laterally extending spacing and attaching flaps 10 or portions 22, fitting against the end walls of the body and abutting against the side walls thereof at the corners of the box. The veneer strips forming the partitions are of a width corresponding to the height of the 15 side and end walls of the box, and the attaching and spacing flanges enable the partitions 21 to be quickly and accurately placed within the body of the box. The spacing and attaching terminal flanges or flaps may 20 be secured to the ends of the box by the adjacent staples 7, which pierce the terminal flaps, the upwardly bent portions of the sheets of the outer layer or thickness and the band 6. The laterally extending terminal 25 flaps or flanges 22 may be left free or loose, as illustrated at 23 in Fig. 6 of the drawings. In this figure, a slight interspace is shown between the laterally extending terminal portions or flaps 22 and the walls of the box 30 to illustrate the loose construction more clearly, but in practice the terminal flaps or portions 22 will fit snugly against the ends of the box and will be retained therein through frictional contact. The partitions, 35 especially when the terminals are attached, are adapted to form resilient supports for the bottles when the box or carton is arranged edgewise with one of its sides resting upon a supporting surface.

40 Certain beers are put up in white bottles, and a rival brewer has spent large sums of money in advertising beer in brown bottles, and has employed noted chemists to show the effect of light on beer. When beer is 45 exposed to light, it gives the beer what is known as a "skunk taste." The veneer carton makes an absolute light-proof package and obviates the necessity of putting a paper jacket over the bottles, which is often done when beer is shipped in light bottles. In practice the carton will be put up in cases holding two dozen bottles, but the capacity 50 of the cases may, of course, be varied.

55 By the term "box element" in the claim, I wish to be understood as comprehending either the cover or body of a veneer package, for as the drawing shows, both the body and the cover 10 are constructed substantially alike, leaving out of consideration the for-

mation of the bottle-receiving compartments 60 provided in the body.

What is claimed is:—

1. In a veneer package, a rectangular box element comprising inner and outer superimposed rectangular sheets of veneer arranged in pairs, said pairs being disposed at right angles to each other, the members of each pair being overlapped at their inner longitudinal edges, said sheets having their terminal portions scored and bent to form 70 wall flanges, a veneer band of a width substantially coextensive with the height of said wall flanges, said band being scored at the corners of the box element and extending around the said wall flanges, and fastening means for securing said band to said flanges, whereby the said band and said flanges constitute the rigid side and end walls of the box element. 75

2. A veneer package of the class described 80 including a rectangular body, and separate spaced partitions dividing the body into central and side portions, and consisting of strips of veneer scored substantially equidistant of their ends and having their terminals bent laterally in opposite directions to form spacing flaps, which are fitted against the opposite walls of the body and abut against the latter at the corners thereof so as to form a guide to position the partitions 85 properly within the body, and fastening means securing the terminals of the partitions to the body and forming a rigid structure. 90

3. A veneer package of the class described 95 including a rectangular body consisting of overlapped sheets of veneer having upwardly bent terminal portions, a band consisting of a strip of veneer and extending around the said upwardly bent terminal 100 portions of the sheets, and separate spaced partitions dividing the body into central and side compartments and consisting of strips of veneer scored at their terminal portions and having their ends bent laterally in opposite directions and fitted against the opposite walls of the body, so as to position the partitions properly within the body and staples piercing the terminal portions of the spacing strips, the upwardly bent terminal 105 portions of the sheets and the said band. 110

In testimony, that I claim the foregoing as my own I have hereto affixed my signature in the presence of two witnesses.

ORIN C. FENLASON.
